UNITED STATES PATENT OFFICE

152,582

DESIGN FOR A MEASURING INSTRUMENT CASE

Gilbert Banever, New Haven, Conn., assignor to
General Electric Company, a corporation of
New York

Application December 26, 1947, Serial No. 143,360

Term of patent 14 years

(Cl. D26—5)

To all whom it may concern:

Be it known that I, Gilbert Banever, a citizen of the United States, residing at New Haven, State of Connecticut, have invented a new, original, and ornamental Design for a Measuring Instrument Case, of which the following is a specification, reference being had to the accompanying drawing, forming a part thereof.

In the drawing, Fig. 1 shows a front perspective view of a measuring instrument case showing my new design, and Fig. 2 is a perspective side view thereof.

This application is a continuation-in-part of my application for design, Ser. No. D. 128,643,

filed April 16, 1946, for a Measuring instrument case.

I claim:

The ornamental design for a measuring instrument case, as shown.

GILBERT BANEVER.
